DESIGN FOR A TONGUE CLEANER

Reinhold Nuessle and Maurice Levy, New York,
N. Y.

Application February 5, 1937, Serial No. 67,468

Term of patent 7 years

To all whom it may concern:

Be it known that we, Reinhold Nuessle and Maurice Levy, citizens of the United States, residing at New York, in the county of New York and State of New York, have invented a new, original, and ornamental Design for a Tongue Cleaner, of which the following is a specification, reference being had to the accompanying drawing, forming part thereof.

In the drawing:

Fig. 1 is a front elevational view of a tongue cleaner showing our new design, and

Fig. 2 is a side edge view of the same.

We claim:

The ornamental design for a tongue cleaner substantially as shown.

REINHOLD NUESSLE.
MAURICE LEVY.
